UNITED STATES PATENT OFFICE.

ALBERT F. ROSE, OF TULSA, OKLAHOMA.

FISHING-TOOL.

1,392,599.

Specification of Letters Patent.

Patented Oct. 4, 1921.

Application filed April 15, 1920. Serial No. 374,091.

To all whom it may concern:

Be it known that I, ALBERT F. ROSE, a citizen of the United States, residing at Tulsa, in the county of Tulsa and State of Oklahoma, have invented certain new and useful Improvements in Fishing-Tools, of which the following is a specification.

My invention relates to means for pulling rods or pipes that have become severed out of well casings, and to means for holding them fast to the hoisting apparatus till they have passed beyond the mouth of the well tubing.

More particularly my invention relates to a fishing tool which is divided in two sections, one section of which passes the collar or flange of the article sought to be recovered while the other section is arrested in its motion till the first named portion has passed by the flange or collar.

Heretofore, there have been many devices used to recover lost articles such as pipes or rods that had slipped or become broken and lodged in well casings. One form of apparatus, which has met with considerable use, is one in which there are two tapered segmental gripping jaws both adapted to slip over the collar or flange on the article at the same time. It has been found that where the flange on the pipe or rod has become bent or distorted that this form of tool will not operate to readily pass thereover. Another form comprises a hollow lug carrier which acts as a receptacle for lugs which may be four or more in number.

This lug carrier fits over the rod or piping to be extracted, and the lugs because of their loose pivoting on bolts and by reason of a split steel spring encircling them, when they pass the lower edge of the collar are pressed inward so that their upper ends are in contact with the pipe below the collar. With this form of apparatus the dirt which may accumulate upon the rod interferes with the

proper contraction of the split steel spring and the lugs do not firmly engage the collar. All sockets made for doing the work of this fishing tool have springs and screws to break loose in the well causing the pulling of the full string of tubing to obtain the screws or springs before the well can be put to pumping. Where slips are used to obtain the same results, they are too thin and invariably break because there is no room between the walls of the tubing for heavy slips to pass the collars on the

tubing on all sides of the tubing at the same time. Likewise these slips have to be recovered by pulling the full string of tubing before the well can be put to pumping as has been mentioned in regard to devices employing springs or screws. It is applicant's intention to devise means for abstracting articles from well tubing that would operate surely and positively and because of its great sturdiness of construction would rarely become inoperative or out of order.

An object of my invention is to provide a fishing tool for well boring apparatus that will have two spears, one of which is slidable upon the other and so arranged that when both the slips have passed the collar or flange on the article sought to be recovered, there will be a positive and certain coöperation between the slips which will obviate any tendency of the rod or pipe to be disengaged and to fall back.

With these and other objects in view which may be incident to the use of the improvements, my invention consists in the parts and combination thereof hereinafter set forth and claimed, with the understanding that the several necessary elements constituting the same, may be varied in proportion and arrangement without departing from the spirit and scope of the invention.

In order to make the invention more clearly understood, I have shown in the accompanying drawings, means for carrying the same into practical effect, without limiting the improvements in their useful applications to the particular constructions which for the purpose of explanation have been made the subject of illustration.

Figures 1 to 5 are side elevations partly in cross section showing the different positions of the tool in operation upon a rod. Fig. 1 shows the position of my fishing tool within the well casing before it has commenced to pass the collars or flanges of the article sought to be recovered; Fig. 2 shows the position while the long spear is passing the collars of the rod; Fig. 3 shows the position in which the short spear is just commencing to pass the collars of the rod; Fig. 4 shows the position in which the short spear has partly completed its movement beyond the collars; Fig. 5 shows the short and long spear both below the flanges or collars and the tool in position for extracting the rod; Fig. 6 is a cross section on line 6—6, Fig. 1; Fig. 7 is a cross section on line 7—7 of Fig.

1; Fig. 8 is a cross section on line 8—8, Fig. 1; Fig. 9 is a cross section on line 9—9, Fig. 1; Fig. 10 is a cross section on line 10—10, Fig. 1; Fig. 11 is a top plan view of the 5 clamp which is placed around the spears just before the end of the extracted rod passes the tube of the well casing.

My tool comprises a long spear 1 fastened firmly to a shank 2 which is angular in 10 cross section, preferably square; shank 2 has a square head 3 of slightly larger cross section than the shank. The head 3 has a lower collar 4 and an upper collar 5. Above the head is located a continuation of the 15 shank having a screw formed thereon at 6 for the purpose of attaching the tool to any suitable rod. The long spear 1 forms a semi-circular shell as plainly indicated in Fig. 9. At the point of juncture of the long 20 spear 1 with the shank 2, there is a horizontally projecting portion 7 through which the shank 2 is fastened. This portion 7 forming the head of the long spear is of substantially circular cross section as indicated 25 in Fig. 8; but has one half of the circular cross section cut away to allow the short spear, to be later described, to slide thereby.

The short spear comprises a head 8 having a hole cut therethrough to allow it to 30 slide upon the square shank 2 and a semi-circular shell body 9 adapted to slide past the head 7 of the long spear.

The whole apparatus is constructed to 35 slide within a casing 10 of the well, and the long spear 1 and short spear 9 are held together by reason of the well casing 10. The short spear 9 is provided with a slip 11 consisting of a thickened end portion of the spear 9 provided with a rounded entering 40 surface to enable it to slide by the collars or flanges on the article to be recovered. Likewise long spear 1 is provided with a slip 12 formed by a thickening of the wall of the end of the spear and also formed with a 45 rounded entering surface. This slip 12 is of considerably greater length than is the slip 11.

A rod 13 upon which this tool is shown in 50 operation is indicated in the drawings. When the fishing tool has been drawn out of the well casing to the point at which the slip of the short spear is just emerging from the edge of the well casing, it is necessary to clamp the long spear 1 and the short spear 55 9 together. To accomplish this there is provided a suitable clamp having arms 14 and 15 which are pivoted at 16 and a wing nut 17 for holding the two arms 14 and 15 in engagement with the spears.

The operation is plainly indicated in the 60 drawings. In Fig. 1 the fishing tool is in position just before the long slip starts to pass the collars on the rod. In Fig. 2 the long slip 12 is passing the collars on the rod 65 13 and is pushing the rod 13 to one side of

the well tubing preventing the short slip 11 from passing by the collars on the rod. The shank 2 has started to slide through the head 8 of the short spear 9. By reason of the square cross section of the shank 2 the 70 head 8 is prevented from any rotation or displacement at any time in its angular relation to the long spear 1. In Fig. 3 the parts are shown in the position in which the long slip 12 has passed beyond the collars 75 on the rod and the short slip 11 is just ready to start passing the collars. In this position by reason of the pressure exerted through the collar 4 against the head 8 the short slip 11 will be forced past the collars on the 80 rod 13. It will be noticed that the long slip 12 by wedging the rod to one side of the well casing prohibits the passage of the short slip 11 until the slip 12 has completely passed the collars on the rod 13, and that 85 after the long slip 12 has passed the collars on the rod 13, the pressure of the head 8 on the short spear 9 will force the rod 13 to the opposite side of the well casing and allow the short slip 11 to pass. Fig. 4 indicates 90 the position in which the short slip is passing the collars on the rod 13. Fig. 5 indicates the position which the parts assume at the time when the tool is in position for the extraction of the rod. Short slip 11 and 95 long slip 12 are both located below the collars on the rod 13 and it is a practical impossibility for the rod to slip between the two.

While I have described but one embodiment of my invention, it is apparent that many modifications may be made therein by those skilled in the art without departing from the spirit thereof, and I desire therefore that my invention be limited only as set 100 forth in the appended claims or by the showing of the prior art.

I claim:

1. In a fishing tool for well boring apparatus, a long spear, an object engaging slip 110 on one end thereof, a shank on the other end, a short spear, an object engaging slip on one end of the short spear coöperating with the slip on the long spear, and means coöperating with the long spear and the short spear 115 holding the two spears in close relation to each other but permitting a relative sliding movement.

2. In a fishing tool for well boring apparatus, a long spear, an object engaging slip 120 on the long spear, a short spear, an object engaging slip on the short spear coöperating with the first named slip to hold an object, and means on the short spear coöperating with the long spear to hold the two spears in 125 close fitting relation but permitting a sliding movement between the two spears.

3. In a fishing tool for well boring apparatus, a long spear, a shank on the long spear, a short spear, a head on the short 130

spear coöperating with the shank to prevent lateral separation of the spears and to guide them in their relative longitudinal movement.

5 4. In a fishing tool for well boring apparatus, a long spear, an angular shank on the long spear, a short spear, a head on the short spear having means to engage the shank to prevent lateral movement of the spears but 10 guiding them in their relative longitudinal movement, and coöperating object gripping parts on each spear.

15 5. In a fishing tool for well boring apparatus, a long spear, an angular shank thereon, a short spear, a head on the short spear slidably engaging the shank to prevent lateral movement of the spears but permitting relative longitudinal movement and coöperating object gripping parts on each of the 20 spears.

25 6. In a fishing tool for well boring apparatus, a long spear, an angular shank thereon, a short spear, a head on the short spear having a hole therein adapted to engage the shank to hold the spears against relative lateral movement but permitting relative longitudinal movement, an object engaging part on one spear coöperating with a similar part on the other spear.

30 7. In a fishing tool for well boring apparatus, a long spear, a short spear, means on the short spear coöperating with means on the long spear whereby the two spears have a longitudinal movement so that whenever 35 the tool is lowered into a well to engage the boring apparatus, the long spear passes one

side of the apparatus while the other spear slides up until the long spear catches beneath a shoulder on the apparatus permitting the apparatus to move toward the long 40 spear and the short spear to pass by the apparatus and engage under a part of the apparatus where, in coöperation with the long spear, it will lift the apparatus on the application of force to the spears. 45

8. In a fishing tool for well boring apparatus, a spear element having a shank, a second spear element having a head engaging the shank of the first element to hold the 50 elements against relative lateral movement but permitting relative longitudinal movement, and an object gripping part on each element coöperating with a similar part on the other for gripping an object.

9. In a fishing tool for well boring apparatus, a spear element semi-circular in cross section, a second spear element semi-circular in cross section, means associated with said elements for guiding them in relative longitudinal movement but preventing relative 60 lateral movement and coöperative object gripping parts on each element.

10. In a fishing tool for well boring apparatus, a spear element semi-circular in cross section, a second spear element semi-circular 65 in cross section and adapted to fit the first element in face to face sliding relation and means associated with said elements for holding them in face to face relation but permitting relative longitudinal movement. 70

In testimony whereof I affix my signature.
ALBERT F. ROSE.
